Specification for Design.

Patented Dec. 12, 1916.

Application filed October 25, 1916. Serial No. 127,716. Term of patent 7 years.

To all whom it may concern:

Be it known that I, CHARLES FORRESTER, a subject of the King of Great Britain, residing in Jersey City, in the county of Hudson and State of New Jersey, have invented a new, original, and ornamental Design for a Rug of Carpet Sizes, of which the following is a specification, reference being had to the accompanying drawing, forming part thereof.

The drawing illustrates a portion of a rug showing my new design.

I claim:

The ornamental design for a rug, substantially as shown.

CHARLES FORRESTER.
